UNITED STATES PATENT OFFICE.

RAYMOND N. HAMILTON, OF MILWAUKEE, WISCONSIN, ASSIGNOR TO MILWAUKEE LACE PAPER COMPANY, OF MILWAUKEE, WISCONSIN, A CORPORATION OF WISCONSIN.

DESIGN FOR A NAPKIN.

Application filed April 13, 1928. Serial No. 26,306. Term of patent 14 years.

To all whom it may concern:

Be it known that I, RAYMOND N. HAMILTON, a citizen of the United States, residing at Milwaukee, in the county of Milwaukee and State of Wisconsin, have invented a new, original, ornamental Design for a Napkin, of which the following is a specification, reference being had to the accompanying drawings, forming a part thereof.

The figure is a top plan view of a napkin, showing my new design in one corner thereof, it being understood that the design as thus shown is repeated in the other three corners.

I claim:

The ornamental design for a napkin, as shown and described.

RAYMOND N. HAMILTON.
